CLAIM

The ornamental design for a box clamp for automobile body straightening unit, as shown and described.

DESCRIPTION

FIG. 1 is a perspective view of a box clamp for automobile body straightening unit showing our new design; FIG. 2 is a side elevational view thereof with the movable jaw in an open position;

FIG. 3 is a bottom plan view thereof;

FIG. 4 is a front end elevational view thereof;

FIG. 5 is a rear end elevational view thereof;

FIG. 6 is a top plan view of the movable jaw shown separately for ease of illustration;

FIG. 7 is a bottom plan view of FIG. 6;

FIG. 8 is a top plan view of the stationary jaw also shown separately for ease of illustration.

FIG. 1

FIG. 2

FIG. 3

FIG. 4

FIG. 5

FIG. 6

FIG. 7

FIG. 8
